UNITED STATES PATENT OFFICE.

MICHAEL FLORANCE O'CONNOR, OF SHERIDAN, WYOMING.

NEUROVERTAMETER.

Application filed June 1, 1925. Serial No. 34,253.

To all whom it may concern:

Be it known that I, MICHAEL F. O'CONNOR, a citizen of the United States, and resident of Sheridan, in the county of Sheridan and State of Wyoming, have invented certain new and useful Improvements in Neurovertameters, of which the following is a specification.

This invention relates to improvements 10 to apparatus employed in chiropractic and it consists of the constructions, combinations and arrangements herein described and claimed.

An object of the invention is to provide 15 an instrument, known as a neurovertameter by virtue of the function that it performs, for the purpose of expediting the analysis and subsequent relocation of subluxated vertebrae in the human spine as one of the 20 necessary operations in chiropractic.

Another object of the invention is to provide a gauge by the initial use of which all necessary data for the customary analysis card can be secured and by the subsequent 25 use of which the data on the analysis card may be used to immediately relocate with absolute certainty the subluxations originally found by palpation and nerve tracing.

Other objects and advantages appear in 30 the following specification, reference being had to the accompanying drawings, in which—

Figure 1 is a side elevation illustrating the neurovertameter in use.

Figure 2 is a detail perspective view of 35 the base bar.

Figure 3 is a detail perspective view of the block upon which the bar is hinged.

Figure 4 is a detail perspective view illustrating the various parts of the measuring 40 sleeve.

Figure 5 is a detail cross section of the standard and base and immediately associated parts.

Figure 6 is a detail cross section taken substantially on the line 6—6 of Figure 1.

Figure 7 is a detail cross section on the line 7—7 of Figure 1.

Figure 8 is a detail cross section on the 50 line 8—8 of Figure 1.

Figure 9 is a detail perspective view of one of the spring clasps in Figures 1 and 8.

Figure 10 is a detail perspective view of the measuring template used in connection 55 with the measuring sleeve.

The foregoing objects of the invention

may be supplemented by a brief statement of the use of the neurovertameter. As already stated, the instrument is used in connection with chiropractic. In this art a 60 spinal analysis of the patient is made either by palpation (exploration of the back of the patient by the fingers of the chiropractor) or by use of such a device as the neurocalometer and palpation. 65

Many backs are hard to palpate due to thickness of tissue, bent spinous processes and very slightly subluxated vertebrae thereby making it necessary to conduct a more or less difficult search or exploration from day 70 to day to locate the foregoing subluxations. It should not be necessary to carry out this process, and it is the purpose of the neurovertameter to eliminate the necessity of this search and to relocate these subluxations 75 with absolute certainty, thereby facilitating the treatment to no small extent.

By applying the neurovertameter immediately following the analysis by palpation or the use of such a device as the neurocalometer and palpation and while the pencil marks indicate the location of subluxated vertebrae are still on the patient's back, measurement is made and recorded on the analysis card showing the table distance 80 used, and the distance each subluxation is from a certain fixed point (the top of the patient's head). By using the same table distance each time, the body will assume the same position and the measurements will 85 always be the same, thereby designating the location of the subluxations, permitting them to be readily found by palpation. 90

The invention comprises an aluminum base bar 1 which is T-shaped in cross section (Fig. 7) to hold the measuring sleeve 2 in place. The measuring sleeve is slideable along the bar, the confronting flanges 3 exerting a sufficient grip upon the base bar to hold the measuring sleeve in any of the 100 various adjusted positions by virtue of certain inherent resiliency in the sleeve itself.

The base bar includes a block 4 to which it is hinged at 5 for a very slight swinging movement. Shoulders 6 and 7 on the bar and block respectively limit the upward movement thus insuring that the bar is perfectly horizontal when the weight 8 is left free to pull up on the base bar by means of the stranded wire cable 9. The block has an opening 10 in which the spindle 11 of the standard 12 fits (Figs. 5 and 6). The base 105

bar is capable of swinging horizontally upon the spindle but is locked in position by means of a set screw 13. The block 4 rides upon a shoulder formed between the standards and the reduced spindle. The spindle carries suitable means 14 to hold the block in place.

An upright arm 15, being a practical continuation of the standard 12, provides the support for the pulley 16 over which the cable runs. The lower extremity of the cable is attached to a screw eye 17 in the extremity of the base bar 1. The pulley 16 is mounted by any suitable means 18. The standard 12 fits into a base 19 in which it is adjusted as to height and held by a thumb screw 20.

Flanges 21 at the sides of the measuring sleeve 2 have openings for the passage of bolts or other securing means 22 by which a head plate 23 and bracket 24 (Figs. 1 and 4) are held together in common. The brackets form part of a rod 25 which is slidable in a socket 26 upon the base bar 1, and held to its adjustment by a thumb screw 27. The socket is suitably attached to the base bar, for example by means of a threaded extension 28 as in Figure 5. Upon loosening the thumb screw 27 the rod 25 is slid in the socket 26 thereby adjusting the measuring sleeve 2 along the bar 1, and the plate 23 in reference to the head of the patient.

A pair of steel spring clasps 29 are intended to grip the sides of the adjusting table T and thus steady the device when in use. These clasps are suitably mounted on the base bar 1, for example by means of a bolt 30 and they are capable of being swung up out of the way when not in use.

A measuring template 31 (Fig. 10) is used in connection with the measuring sleeve 2. This template is composed of a flat metal sheet having a slot 32 which permits slipping over the measuring sleeve (Fig. 1). The sides of the slot are graduated in inches as at 33, and the lower edges of the template at the lateral sides of the slot are also graduated in inches as at 34.

The sides and top of the measuring sleeve 2 are graduated in inches as at 35. These various graduations are important in marking locations on the back of the patient as presently appears. The template 31 has an opening 36 by means of which it is readily handled by the operator.

The operation is readily understood. As before stated, the impinged nerves are located either by palpation or by means of such a device as the neurocalometer, the patient being seated, pencil marks being made on the patient's back showing the locations of the impinged nerves mentioned. By vertebral palpation the vertebrae causing the impingement of the nerves are located and pencil marks are made on the

patient's back showing the locations of the subluxated vertebrae. The patient is then placed face downward on the adjusting table T, the head piece of which is split, care being taken to obtain the correct distance between the front and back parts of the adjusting table (known as the table distance). 70

Careful palpation is again made relocating the subluxated vertebrae, this being necessary for the reason that the pencil marks sometimes change position as compared with the location of the subluxated vertebrae when the patient is seated. When these subluxations have been carefully located and pencil marks are made on the patient's back indicating the location, a record of the locations of the subluxations is made through the aid of the improved neurovertameter as follows: 75

The bar 1 is swung around over the patient's back and lowered by means of the thumb screw 20 so as to touch the patient's head, the spine between the shoulders and the center of the sacrum (Fig. 1). The spring clasps 29 are swung down to grip the sides of the adjusting table so as to steady the bar 1. 80

Upon loosening the thumb screw 27 the measuring sleeve 2 is slid along the bar 1 until the head plate 23 rests against the top of the patient's head. The thumb screw 27 is then tightened, keeping the head plate resting against the patient's head. The measuring template 31 is now fitted over the measuring sleeve 2 to find the distance from the top of the patient's head to the various subluxations, as follows: 85

The measuring template 31 is made to straddle the measuring sleeve 2 so that it fits at right angles thereto, the lower edge being brought into registration with one of the pencil marks on the patient's back. This mark indicates the location of the first subluxation. By keeping the template upright and parallel with the graduations 35 on the sleeve 2 the number of inches from the top of the patient's head to the subluxation A will be registered on the measuring sleeve. The vertical graduations 33 on the template 31 may be employed as auxiliary checks in keeping account of the distance between the bottom of the measuring sleeve 2 and the surface of the patient's back. The graduations 34 can be used to detect a right or left high hip (bone), and to locate the apex of the lateral curvature of the spine caused by same. Record is made of all other pencil marks (there usually being several) in a similar manner. 100

When the patient returns for another adjustment from the original analysis he is at once placed upon the adjusting table, using the same table distance as used in the analysis. The bar 1 of the neurovertameter 105

is swung around over the patient's body and lowered as before over the head, the spine between the shoulders, and the center of the sacrum. The measuring sleeve 2 is then 5 moved along until the head plate 23 rests against the head. The thumb screw 27 is tightened. By use of the movable measuring template 31 and by the measurements recorded upon the analysis card it becomes 10 an easy matter to relocate the former subluxations and to indicate them on the patient's back by means of pencil marks such as A (Fig. 1). The neurovertameter is then swung back parallel with the wall of 15 the room, out of the way. Needed adjustments are then made according to the pencil marks on the patient's back.

While the construction and arrangement of the improved neurovertameter or gauge 20 is that of a generally preferred form, obviously modifications and changes may be made without departing from the spirit of the invention or the scope of the claims.

I claim:

25 1. A device for assisting the recording and the relocation of subluxations in chiropractic and comprising a graduated measuring element, means by which said element is held suspended in the direction of the 30 spine of a human body to be treated, means associated with said element to touch a portion of said body thereby to establish a gauge for the positioning of said element, and a movable template to straddle said element and contact the body, said template having graduations coacting with said element and with the surface of the body to fix the desired locations.

2. A gauge for use in combination with an 40 adjustment table in the art of chiropractic and comprising a fixture, a measuring element carried by said fixture for free swinging motion from side to side including a position over said table and human body 45 reclining thereon, means associated with the measuring element to grip a portion of the table and thereby steady said element, means associated with said element to touch a portion of the body and thereby establish pre- 50 determined relationship of said element with said body, and a freely movable template straddling and coacting with the measuring element and said body to establish the location of certain desired regions upon said body.

3. A device for use in combination with an 60 adjustment table in the art of chiropractic and comprising a fixture, a gauging element swingably mounted upon said fixture and intended to be swung in position over a body reclining on the table, and resilient means carried by said gauging element to temporarily grip a portion of the table while said element is in operative use.

65 4. A device for use in combination with

an adjustment table in the art of chiropractic and comprising a fixture, a gauging element swingably mounted upon said fixture and intended to be swung in position over a body reclining on a table, resilient means 70 carried by said gauging element to temporarily grip a portion of the table while said element is in operative use, and means incorporated in said fixture and permitting adjustments of said standard to bodily raise 75 and lower said gauging element and said gripping means in respect to the body and table.

5. A neurovertameter comprising a standard, a base bar carried thereby, means to support said base bar in a substantially parallel position in respect to and above the spine of a human body, a graduated measuring sleeve slidable upon said bar, a head plate carried by said sleeve intended to touch the head of the body to establish a relationship of the measuring sleeve with the body, to fix the position of said sleeve and plate upon the bar, and a template fitted over the measuring sleeve and being used in a predetermined manner in connection therewith in order to establish certain locations upon the surface of said body.

6. A neurovertameter comprising a standard, a base bar swingably mounted upon the standard, means by which the base bar is suspended upon the standard in position over a human body to be treated, a graduated measuring sleeve slidable upon the bar but frictionally held thereon during adjustment, a plate to touch the head of the human body and thereby establish the relationship of said sleeve to the body, a rod secured in common through the plate and sleeve, means by which the rod can be secured to the bar to fix the adjustment of said sleeve, and a measuring template having a slot permitting straddling of the measuring sleeve to coact with the graduations thereof to establish certain desired locations upon said body.

7. A neurovertameter comprising a fixture including a base and a standard which is adjustable in respect thereto, a block swivelly but adjustably mounted upon the standard, a T-shaped base bar hinged upon said block and having limited movement in respect thereto, suspending means for the bar including a weighted cable supported by the standard, a graduated measuring sleeve slidable upon the bar, a head plate having a rod, means securing the rod, head plate and measuring sleeve together, means on the bar including a socket and thumb screw coacting with the rod and securing adjustments of the measuring sleeve, and a measuring template arranged to straddle the measuring sleeve and coact with the graduations thereof in determining desired locations upon a body to be treated.

MICHAEL FLORANCE O'CONNOR.
